Canada LLP; Alexandre Daoust

(57) **CLAIM**

The ornamental design for a buckle, as shown and described.

DESCRIPTION

FIG. 1 is an oblique view of a first embodiment of a buckle showing my new design;

FIG. 2 is right side view thereof;

FIG. 3 is a left side view thereof;

FIG. 4 is a front view thereof;

FIG. 5 is a rear view thereof;

FIG. 6 is a top plan view thereof;

FIG. 7 is a bottom view thereof.

FIG. 8 is an oblique view of a second embodiment of a buckle showing my new design;

FIG. 9 is right side view thereof;

FIG. 10 is a left side view thereof;

FIG. 11 is a front view thereof;

FIG. 12 is a rear view thereof;

FIG. 13 is a top plan view thereof; and,

FIG. 14 is a bottom view thereof.

The bottom of both the first embodiment and the second embodiment are unornamented and do not form part of the claimed design. The metallic surface finish shown in the figures does not form part of the claimed design. Similarly, the metallic color does not form part of the claimed design.

1 Claim, 14 Drawing Sheets
